TWISTING MACHINE

George E. Henning, Baltimore, Md., assignor to
 Western Electric Company, Incorporated, New
 York, N. Y., a corporation of New York

Application October 18, 1946, Serial No. 704,157

6 Claims. (Cl. 57—13)

1

This invention relates to twisting machines and particularly to twisting machines for forming highly flexible, close spiral cordage.

In the communications field, many types of apparatus require the use of a highly flexible cord and also a cord which will stand a maximum number of flexings without breakage of the individual conductors which make up the cord. These flexible cords generally comprise a plurality of individually insulated, stranded conductors twisted together to form a composite core over which there is applied a suitable insulating jacket, which jacket may be formed of rubber, or a rubber-like compound or a suitable textile covering. In order to form a cord having maximum flexibility, the spirals of the individual conductors twisted together to form the composite core must lay against each other throughout the entire length of the core, which type of composite core will hereinafter be referred to as a close spiral composite core.

The composite core unit is usually formed by a twisting machine provided with a rotating flyer unit, which serves to twist together a plurality of conductors being continuously advanced thereto. In such a twisting operation, the conductors are usually drawn from a group of supply reels positioned some distance from the flyer, whereupon the twist imparted to each of the conductors by the flyer is carried back along the conductor to a point where each conductor engages a guide member. In other words, the guiding members serve to check the twisting action on the conductors, whereby the twisting point of the conductors occurs at some point intermediate the flyer and the guiding members. It has been found that the twisting point of the conductors tends to surge back and forth between the flyer and the guiding member due to the inherent resiliency of the conductors and the spring action of the close spiral being formed by the flyer.

Therefore, in order to produce a smooth, uniform close spiral core, it is necessary to hold the twisting point of the conductors at some fixed point with respect to the flyer.

An object of the invention is to provide new and improved twisting machines.

A further object of the invention is to provide new and improved twisting machines for making close spiral cordage.

With these and other objects in view, one apparatus embodying the invention comprises an adjustable supporting member having a plurality of guide pulleys rotatably mounted thereon which serve to direct a plurality of insulated conductors

2

from a supply source at a substantially sharp angle toward the center of a twisting head provided on a rotatable flyer unit. A tubular restraining member is centrally positioned on the adjustable plate with respect to the guide pulleys for holding the twisting point of the conductors as close to the twisting head as possible.

A clear understanding of the invention may be had by reference to the following detailed description of a specific embodiment thereof, when read in conjunction with the appended drawings, in which:

Fig. 1 is a fragmentary, side elevation of a twisting machine forming a specific embodiment of the invention;

Fig. 2 is an enlarged, vertical sectional view of a portion of the machine shown in Fig. 1;

Fig. 3 is an enlarged, fragmentary, sectional view taken along line 3—3 of Fig. 2, and

Fig. 4 is an enlarged, fragmentary view illustrating the twisting operation performed on the conductors by the twisting machine.

The following description is directed to twisting machines for making four-conductor, close spiral cordage, it being understood that the apparatus may be used to twist together various types of strands and in various group combinations as desired.

Referring now to the drawings, attention is first directed to Fig. 1, in which a portion of a twisting machine is illustrated therein as being comprised of a flyer 10 rotatably mounted between a pair of spaced standards 11—11 by means of a hollow trunnion 12 and a hollow trunnion 13 formed integrally with and on opposite ends of the flyer 10. There is provided on the flyer 10 a pair of capstans 15—15 driven at a constant rate of speed by an externally disposed change gear mechanism 16, which gear change mechanism, together with the flyer 10, is driven by a shaft 17 connected to a suitable driving means (not shown).

The operation of the flyer 10 and the gear change mechanism 16 is described fully in G. E. Henning et al. Patent 2,338,848, issued January 11, 1944, and copending application Serial No. 704,132, filed October 18, 1946, by E. D. Hanson, G. E. Henning and O. G. Nelson.

When the flyer 10 is rotated in the proper direction, a plurality of insulated conductors 20—20 are advanced from a suitable supply (not shown) through a strand guiding unit 21 and twisted around a textile strand 22 also being advanced through the unit 21 to form a close spiral composite core 23 (Figs. 2 and 4). The core 23 is

advanced through the central hub of a serving head 24 by the aid of which a textile covering is wrapped around the composite core to form a core unit 25. The core unit 25 is advanced laterally along the central axis of the hollow trunnion 12 by the capstans 15-15 mounted on the flyer 10, the core unit 25 being passed alternately around each of the capstans a given number of times and then directed therefrom to a pulley 26 and thence to a pulley 27 rotatably mounted on a reciprocating distributor nut 28 carried by the flyer 10. The distributor nut 28 is also driven by the change gear mechanism 18 and serves to reciprocate the pulley 27 so as to lay the unit 25 in even layers on a takeup reel 30 rotatably mounted on the central axis of the flyer.

For a complete understanding of the apparatus for driving the takeup reel 30 in such manner that a constant tension is maintained on the core unit 25 as it is wound on the reel, attention is again directed to the above mentioned patent and copending application.

In order for the flyer 10 to produce a close spiral core, such as the core 23 (Fig. 4), it is necessary that suitable conductor guiding apparatus, such as the conductor guiding unit 21, be positioned in such a manner that the twisting point of the various conductors which comprise the composite core 23 will be maintained at a fixed point with respect to the means provided on the flyer 10 which imparts the twist to the conductors.

The conductor guiding unit 21 comprises a vertically positioned circular plate 35 having secured adjacent to the outer periphery thereof and equidistant from each other a plurality of tubular bearings 36-36. Each of the bearings 36-36 slidably engages a rod 37 horizontally aligned therewith and rigidly positioned around the periphery of a circular base plate 40. The conductor guiding unit 21 is rigidly mounted adjacent to the flyer so that its central axis is aligned with the central axis of a twisting head 31 secured on the end of a tubular bushing 32 threadedly mounted on an end 33 provided on the trunnion 12 of the flyer. The twisting head 31 is provided with a bore 34 which is designed to engage the core unit 25 tightly so that when the twisting head is rotated by the flyer, it will turn the core unit 25 therewith and without any radial slippage occurring between the core unit and the twisting head, thereby twisting the conductors 20-20 together to form the composite core 23.

Four brackets 41-41 are secured on the inner face of the plate 35 equidistant from each other and from the central axis of the plate by means of studs 42-42 threadedly mounted in the plate 35. Each of the brackets 41-41 is provided with a pair of spaced supports 43-43 between which is rotatably mounted a grooved pulley 44 by means of a pin 45 positioned in bores provided in the spaced supports 43-43. A plurality of bores 46-46 are provided in the plate 35, each bore 46 being horizontally aligned with an aperture 47 provided in the base of each of the brackets 41-41. The bores 46-46 and 47-47 provide a plurality of openings through which the conductors 20-20 may pass from a suitable supply source (not shown) to the grooves provided in the pulleys 44-44.

An elongated bushing 50 is centrally positioned on the plate 35 and is provided with a bore 51 in which a restraining member 52 is slidably positioned, the restraining member 52 being maintained in any selected position in the bushing 50

by means of a set screw 53 threadedly mounted in the wall of the bushing. The restraining member 52 is provided with a conical end 54 and a central bore 55 through which the textile strand 22 is advanced by the twisting machine during a twisting operation on the conductors 20-20. A set screw 56 is provided in each of the bushings 36-36 for the purpose of selectively positioning the guiding unit 21 with respect to the twisting head provided on the flyer 10. The position of the guiding unit 21 with respect to the twisting head 31 determines the angle at which the conductors 20-20 are directed toward the central axis of the core 23, which angle in turn determines the lay or pitch of the helices formed in the core 23. To twist together a plurality of conductors having an inherent resilience which resists the twisting action so that the individual convolutions or helices lay against each other throughout the core, such as the core 23 (Fig. 4), it is necessary to position the guide pulleys 44-44 so that the individual conductors are directed toward the axis of the core at such an angle that a close spiral core results and the conductors contact the central axis of the core at a point close to the twisting head.

The restraining member 52 is adjustably mounted on the guiding member 21 so that its conical end 54 may be selectively positioned with respect to the end of the twisting head 31 and the pulleys 44-44. This arrangement permits adjustment of the restraining member to a position which maintains the twisting point of the conductors 20-20 as close to the twisting head 31 as is required to produce the close spiral core 23 and prevents the twisting point from surging back and forth along the central axis of the core 23, which surging effect is caused by the inherent resiliency of the insulated conductors 20-20 and the spring action of the close spiral core.

The capstans 15-15 continuously advance the core 23, formed by the twisting head, away from the conical end of the restraining member 52, and laterally through the bore 34 of the twisting head 31. Immediately before the core 23 advances into the bore of the twisting head, the serving head 24 serves a textile covering over the core 23 to form the core unit 25. The serving head 24 comprises a rotor 55 rotatably mounted on a tubular support 56 centrally positioned on the base plate 40 by means of needle bearings 57-57 mounted within a central hub portion 60 of the rotor 55. A pulley 61 is keyed to the hub 60 and engages a V-belt 62 connecting the pulley 61 with a pulley 63 provided on a variable speed reducer 64 (Fig. 1). The speed reducer 64 is also driven by the shaft 17 by means of a V-belt drive 65.

A plurality of spindles 66-66 are rigidly secured on the rotor 55 equidistant from each other and from the central axis of the serving head, which spindles serve to rotatably support a plurality of strand supply cops 67-67. A strand 70 is drawn from each cop 67 threaded through a guide 71 positioned on the rotor 55 adjacent to the respective cop, thence through a guide 72 positioned on a strand guiding member 73 secured on the hub 60 of the rotor, and thence through a radial slot 74 provided in the end of the member 73 to the core 23 being formed by the twisting head. The speed reducer 64 is arranged to rotate the rotor 55 in the same direction as the flyer 10, the twisting head 31 and the core 24 rotating therewith, but at a substantially greater

rate of speed so that the serving head 24 is able to serve a textile covering over the core 23.

It is believed to be apparent that when the rotor 24 is rotated in the same direction as the twisting head 31, the strands 70-70 are withdrawn from the cops 67-67 and spirally wrapped around the core 23 just before it enters the bore 34 of the twisting head 31 (Fig. 2). It will be noted that the strands 70-70 are wrapped around the core in a direction opposite to that in which the spirals of the core are formed. While the strands 70-70 may be served in either direction on the core 23, it is believed to be obvious that the serving of the strand in an opposite direction to that of the spirals of the core serves to hold the close spiral core tightly together.

The holding of the twisting point of the conductors close to the end of the twisting head by proper adjustment of the guiding unit 21 and restraining member 52, permits simultaneous serving of the textile covering around the twisted core 23 immediately after it is formed. If, however, the twisting point were not so confined but allowed to surge back and forth, it is apparent that serving would sometimes take place around the core before it was fully formed and there would result a very uneven and imperfect core.

The above-described apparatus operates in the following manner:

A plurality of individual insulated conductors 20-20 (in this case four) are taken from a suitable supply (not shown), and are passed through the bores 46-46 and 47-47 to their respective guide pulleys 44-44 and thence through the bore 34 provided in the twisting head 31 together with the textile core 22, which is drawn through the central bore 55 of the restraining member 52. The conductors and the strand then pass through the bushing 32, the hollow trunnion 12 of the flyer 10, and then alternately around the capstans 15-15 several times to the guide pulley 26 mounted on the opposite side of the flyer. The pulley 26 directs the conductors and the strand directly to the distributing pulley 27 from which the conductors 20-20 and the strand 22 are directed to the winding surface of the takeup reel 30, the conductors and the strand being secured thereto as a unit so that when the reel is rotated it will take up the core unit 25.

When the flyer 10 and the capstans 15-15 are driven at constant rates of speed, the twisting head 31 driven by the flyer serves to twist the conductors 20-20 spirally together and around the textile strand 22 to form the close spiral composite core 23, and the capstans continuously advance the conductors and the strand from their respective supplies to the guide pulleys and the twisting head. In order to produce a close spiral core 23, it is necessary that the twisting point of the conductors 20-20 which is the formation point of the core 23 be maintained at a fixed point with respect to the twisting head 31 and close to the twisting head. Even though the flyer 10 and the capstans 15-15 are being driven at the proper rates of speed with respect to each other, the twisting point of the individual conductors 20-20 has a tendency to surge back and forth between the end of the twisting head 31 and the peripheries of the guide pulleys 44-44 unless prevented from being so, because of the inherent resiliency of the individual insulated conductors 20-20 and the spring action of the close spiral being formed by the twisting head 31.

This surging of the twisting point of the con-

ductors is prevented by the restraining member 52, which may be adjusted so that the conical end 54 thereof engages each of the conductors 20-20 as they contact the central axis of the core 23 and causes all the twisting of the conductors to take place against the conical end 54 and close to the twisting head.

The capstans also continuously advance the close spiral core 23 away from the end of the restraining member and toward the bore of the twisting bushing. The serving head 24 is arranged with respect to twisting head so that its rotor 55, when rotated as described hereinabove, will withdraw the strands 70-70 from the supply cops 67-67 and serve the strands spirally around the core 23 as it travels between the restraining member 52 and the end of the twisting head. The serving of the strands around the core 23 produces a textile covering therearound and completes the core unit 25, strands of the covering being wrapped around the core in a direction opposite to that in which the spirals of the core are formed. This arrangement of the textile covering with respect to the composite core serves to hold the spirals in their close relationship.

The core unit is advanced through the bore 34 of the twisting head 31, which bore is designed to engage the core unit tightly and thereby impart all of the twist to the conductors 20-20 necessary to form the close spiral core 23. By virtue of the fact that the bore 34 engages the core unit tightly, it also serves to smooth out the textile covering formed by the serving head 24, and to compress the core unit 25 into a compact unit. After being advanced through the bore of the twisting head, the core unit passes around the capstans 15-15 in a crisscross manner and is directed therefrom to the guide pulley 26 mounted on the flyer 10. The guide pulley 26 directs the core unit to the distributor pulley 27 which serves to distribute the core unit evenly upon the takeup reel 30 mounted in the flyer and driven by externally disposed means (not shown) so as to maintain uniform tension on the core unit 25.

While the above-described apparatus is particularly well adapted to make four-conductor close spiral cordage, it is readily seen that the apparatus may be easily modified so as to produce close spiral cordage having any reasonable number of conductors, such as 2, 3 or 6 conductors. In addition, the apparatus may be modified to twist a plurality of filler cords in with the close spiral core. It is believed to be apparent that the embodiment of the invention described herein is merely illustrative and may be modified without departing from the spirit and scope of the invention.

What is claimed is:

1. In a twisting machine having a cradle type, rotatable flyer arranged to twist together inherently resilient conductors being advanced thereto by capstans disposed in the flyer, the improvement which comprises means centrally positioned on the end of the flyer and rotatable therewith for twisting together a plurality of such conductors being advanced by the capstans into a composite core, means for guiding the conductors toward the central axis of the twisting means, means for adjusting the position of the guiding means to so direct the conductors to the end of the twisting means that the twisting point of the conductors occurs close to the end of the twisting means and the conductors will be twisted together into a close spiral core, and means rotat-

able about the central axis of the twisting means for serving a textile covering around the composite core immediately after the core is formed by the twisting means.

2. In a twisting machine having a cradle type rotatable flyer arranged to twist together inherently resilient conductors being advanced thereto by capstans disposed in the flyer, the improvement which comprises means externally positioned along the central axis of the flyer for twisting together a plurality of such conductors being advanced by the capstans into a composite core, means for guiding each individual conductor toward the central axis of the twisting means, means for supporting the conductor guiding means equidistantly about the central axis of the twisting means, means for adjusting the supporting means carrying said guiding means to direct the conductors guided thereby so that they will be twisted together close to the end of the twisting means and at such an angle that they will be twisted together into a close spiral core, means rotatable about the central axis of the twisting means for serving a textile covering around the close spiral core at the end of the twisting means, and means for holding the twisting point of the conductors at a fixed point with respect to the end of the twisting means to assure that the close spiral core is completely formed by the twisting means before the textile covering is served around the core.

3. In a twisting machine having a cradle type rotatable flyer arranged to twist together inherently resilient conductors being advanced thereto by capstans disposed in the flyer, the improvement which comprises means externally disposed along the central axis of the flyer and having a bore therethrough for tightly engaging a plurality of such resilient conductors being advanced by the capstans and twist them together into a close spiral core when the flyer is rotated, rotatable means for guiding the conductors toward the end of the twisting means, means for supporting the guiding means equidistantly about the central axis of the twisting means, means for adjustable positioning the supporting means carrying the guiding means to direct the conductors to the twisting means so that the twisting point of the conductors occurs close to the end of the twisting means and at such an angle that the conductors are twisted together into a close spiral core, and means rotatable about the central axis of the twisting means for serving a plurality of textile strands around the close spiral core at the end of the twisting means, whereby the restraining member permits the twisting means to produce a uniformly twisted core against the action of the inherent resilience of the conductors.

4. In a twisting machine having a cradle type rotatable flyer arranged to twist together inherently resilient conductors being advanced thereto by capstans disposed in the flyer, the improvement which comprises a tubular hub mounted adjacent to the end of the flyer, an elongated bushing externally disposed along the central axis of the flyer so as to extend through the tubular hub and rotatable with the flyer, a twisting head mounted on the free end of the bushing for gripping a plurality of such conductors and twisting them together into a composite core when the flyer is rotated, means rotatably mounted on the hub for serving a textile covering around the core at the end of the twisting head, means for guiding the individual conductors toward the end of the twisting head, means for adjusting the posi-

tions of the guiding means so that they will so direct the conductors that they will be twisted together by the twisting head into a close spiral core in advance of the point at which the textile covering is applied by the serving means, and means for engaging the conductors at the twisting point to hold the twisting point close to the end of the twisting head.

5. In a twisting machine having a cradle type rotatable flyer arranged to twist together inherently resilient conductors being advanced thereto by capstans disposed in the flyer, the improvement which comprises a stationary tubular hub mounted adjacent to the receiving end of the flyer, an elongated bushing extending externally through the tubular hub along the central axis of the flyer and rotatable with the flyer, a twisting head mounted on the free end of the bushing for tightly gripping a plurality of conductors being advanced by said capstans and imparting all the twist to the conductors when the flyer is rotated, means for guiding each individual conductor toward the central axis of the twisting means, means for supporting the conductor guiding means equidistantly about the central axis of the twisting means, means for adjusting the guide supporting means to direct the conductors guided thereby so that they will be twisted together close to the end of the twisting means and at such an angle that they will be twisted together into a close spiral core, means rotatable about the central axis of the twisting means for serving a textile covering around the close spiral core at the end of the twisting means, and means for holding the twisting point of the conductors at a fixed point with respect to the end of the twisting head to assure that the close spiral core is completely formed by the twisting means before the textile covering is served around the core.

6. In a twisting machine having a flyer rotatable about its central axis to twist together inherently resilient conductors being advanced thereto by capstans disposed in the flyer, the improvement which comprises an elongated bushing externally disposed along the central axis of the flyer and rotatable therewith, a tubular twisting head positioned on the end of the bushing for twisting together a plurality of such conductors being advanced by the capstans when the flyer is rotated, rotatable means for guiding each individual conductor toward the central axis of the twisting head, means for supporting the guiding means equidistantly about the central axis of the twisting head, said supporting means being adjustable with respect to the twisting head whereby the guiding means carried thereby may be positioned to so direct the conductors so that they will be twisted together close to the end of the twisting head and at such an angle with respect to the central axis of the twisting head that they will form a close spiral core, means for serving a plurality of textile strands spirally around the core at the end of the twisting head, said serving means including a rotor rotatably mounted about the central axis of the bushing and twisting head, a plurality of strand supply cops rotatably mounted on the rotor and externally disposed means for rotating the rotor in the same direction as the twisting head but at a substantially greater rate of speed whereby when the rotor is rotated a strand is withdrawn from each of the cops and served spirally around the close spiral core in a direction opposite to that in which the spirals of the core are formed by the twisting head, and a restraining member centrally dis-

posed on the supporting means and having a conical end provided thereon, said restraining member being adjustably positioned on the supporting means so that the conical end thereof may be positioned directly against the conductors as they contact the central axis of the core, whereby the twisting point of the conductors is maintained at a fixed point close to the end of the twisting head thereby enabling the twisting head to produce a uniformly twisted core over which the textile covering is applied.
